[57] CLAIM

The ornamental design for a blower outlet fitting, as shown and described.

DESCRIPTION

FIG. 1 is a perspective view of a blower outlet fitting showing my new design;

FIG. 2 is a side elevational view, the opposite side being a mirror image thereof;

FIG. 3 is a front elevational view thereof;

FIG. 4 is a rear elevational view thereof;

FIG. 5 is a top plan view thereof; and,

FIG. 6 is a bottom plan view thereof.

The broken line showing of the blower in FIG. 1 is for illustrative purposes only and forms no part of the claimed design.
